UNITED STATES PATENT OFFICE

2,621,488

FREEZING CONTAINER

Joseph E. Layton, Hinsdale, Ill., assignor to International Harvester Company, a corporation of New Jersey

Application November 18, 1950, Serial No. 196,464

12 Claims. (Cl. 62—89)

1

The present invention relates to freezing containers and more particularly to an ice forming container having means for ejecting the ice.

With the introduction of the mechanical refrigerator into the homes, the problem of removing ice cubes from ice trays has been encountered. In the earlier types of refrigerators, it was necessary to remove the ice tray from the refrigerator and run warm water over it in order to break the bond between the tray and the ice before the ice cubes could be removed. In recent years many types of trays have been developed whereby the cubes can be removed without the necessity of running warm water over the tray, but in most of these it is still necessary to remove the tray from the refrigerator before the cubes can be separated from the trays. Another disadvantage present in many of these trays is that in breaking the bond between the ice and tray all the cubes in the tray are removed and if only a few cubes are desired it is very difficult to fit the remaining cubes back into the tray.

An object of the present invention is to provide a refrigerator with an ice forming device which is so constructed that ice cubes may be ejected therefrom one at a time.

Another object of the invention is to provide a refrigerator with an ice forming container from which ice cubes may be removed without requiring removal of the container from the refrigerator.

Still another object of the invention is to provide an ice forming device with a novel ice ejecting means which may be easily operated.

A further object of the invention is to secure an ice forming device to a door of a refrigerator so that when ice cubes are desired, they will be readily available when the door is open.

Further objects and advantages of the present invention will become more apparent when considered in connection with the following description and accompanying drawings, wherein:

Fig. 1 is a front elevational view of the top portion of a refrigerator cabinet.

Fig. 2 is a cross-sectional view of an ice container taken on line 2—2 of Fig. 1.

Fig. 3 is a cross-sectional view of the ice container taken on line 3—3 of Fig. 2.

Fig. 4 is a cross-sectional view of the ice container at 45° rotation.

Fig. 5 is a cross-sectional view of the ice container at 90° rotation.

Fig. 6 is a cross-sectional view of the ice container at 135° rotation.

Fig. 7 is a cross-sectional view of the ice container at 180° rotation.

2

Fig. 8 is a cross-sectional view of a modified ice container.

Fig. 9 is a cross-sectional view of the modified ice container of Fig. 8 taken on line 9—9.

5 Fig. 10 is a cross-sectional view of the modified ice container with a single ice container rotated 45°.

Fig. 11 is a cross-sectional view of the modified ice container with a single ice container rotated 10 90°.

Fig. 12 is a cross-sectional view of the modified ice container with a single ice container rotated 135°.

Referring more particularly to the drawing, 15 there is shown a portion of a refrigerator cabinet 10 having a horizontal evaporator 11 which forms the walls of a fast freezing compartment 12 located in the upper portion of the food storage compartment 13. The specific design of the evaporator 11 is not material and can be of any of the well-known types through which refrigerant is circulated which absorbs heat from the air within food storage compartment 13 and fast freezing compartment 12. The front of compartment 12 is closed off from compartment 13 by doors 14 which are vertically hinged to evaporator 11.

30 A plurality of ice forming containers 15 are secured to the inner wall 16 of the doors 14. Each container is provided with bottom 17, inclined front wall 18, inclined side walls 19 and 20, and rear wall 21 which extends above the top edges of the other walls. Rear wall 21 is provided with a recessed portion 22 having a hole or socket 23 therethrough and a semi-circular slot 24 which extends approximately 180° around socket 23. Pivot pin or rod 25 is secured to inner wall 16 and extends into socket 23. Ends 26 and 27 are both peened over in order to permanently secure the container 15 to the door 14. The diameter of rod 25 is slightly smaller than the diameter of socket 23 in order to provide a 35 sliding fit so that the container 15 may be rotated about rod 25.

An ejector arm 28 having a vertically extending leg 29 and a horizontally extending leg 30 is 45 provided for each container. Leg 29 is disposed adjacent to back wall 21 and has a socket 31 which fits over pivot rod 32. Pivot rod 32 extends through slot 24 and is secured to inner wall 16 on the same vertical line as rod 25 between bottom wall 17 and rod 25. Ends 33 and 34 of rod 25 are peened over in order to secure arm 28 to inner wall 16. The diameter of rod 32 is 50 slightly smaller than the diameter of socket 31 in order to allow rotation of the ejector arm 28

about rod 32. Leg 30 is disposed adjacent to bottom wall 17 with edges 35 and 36 spaced slightly from side walls 19 and 20 respectively.

The containers 15 are spaced along the width of the evaporator doors 14 so that each may be rotated approximately 180°. The container is filled to any desirable height with a liquid to be frozen into an ice cube. When an ice cube is desired, container 15 is rotated about pivot rod 25 as shown in Figs. 4, 5, 6, and 7. During this operation, edge 35 of horizontal leg 30 will slide along side wall 19 and ejector arm 28 will be rotated about pivot rod 25. Leg 29 will move relative to back wall 16 and break the bond between the ice and back wall 16. Since the distance from pivot rod 32 to leg 30 is shorter than the distance from pivot rod 25 to the container's bottom 17, leg 30 and bottom wall 17 will part from each other during the rotational movement. Since the ice cube is supported above leg 30, it will be ejected upwardly so that the bond between the ice and side walls 19 and 20, front wall 18 and bottom wall 17 will be completely broken. At 90° of rotation as shown in Fig. 5, the leg 30 and bottom wall 17 will have parted a distance approximately equal to the distance between the centers of pivot rod 25 and pivot rod 32. At 180° of rotation as shown in Fig. 7, the leg 30 and bottom wall 17 will have parted a distance approximately equal to twice the distance between the centers of pivot rod 25 and pivot rod 32. It will be necessary to rotate the container only far enough that the operator may grasp the top of the ice cube and remove it from the container, or until the ice cube falls out of the container.

Figs. 8-12 show a modification in which several containers 39 are grouped together in series on the rear wall 16 of the door 14. Each container has a bottom wall 40, sloping front wall 41 and side walls 42 and 43, and a rear wall 44 which is pivotally secured to pivot rod 45. The pivot rod 45 is secured to rear wall 16 and acts as a common pivot rod for several containers 39. Back wall 44 is provided with a socket 46 which fits over pivot rod 45 and a semi-circular slot 47 which extends approximately 180° about socket 46. A second pivot rod 48 is secured to rear wall 16 on the same vertical line as pivot rod 45 between bottom wall 40 and pivot rod 45. Pivot rod 48 extends through slots 47 and ejector arms 49 are pivotally mounted thereon. An ejector arm is provided for each container and has a first leg 50 disposed adjacent back wall 44 and a second leg 51 disposed adjacent bottom wall 40.

The series of containers 39 are positioned on the evaporator doors 14 in spaced relationship so that each container may be separately rotated and the doors 40 may be opened. As shown in Figs. 10, 11 and 12 the container 39 is rotated in the same manner as container 15 as explained above so that the bond between the ice cube and the container 39 is broken and the ice cube will drop out of the container. Since leg 50 will contact pivot rod 48 at approximately 135° of rotation as shown in Fig. 12, it is not possible to rotate container 39 past this point. However, the ejector arm will have moved far enough to have completely broken the bond between the ice cube and the walls of container 39 so that the cube will drop out of the container. The distance between pivot rod 45 and the top edges of side walls 42 and 43 is greater than the distance from the bottom wall 40 to the top edges of the side walls so that the ice cube will slide free between

pivot rod 45 and the top edges of the container walls.

It is to be understood that many changes could be made in carrying out the above construction without departing from the scope of the invention, and it is intended that all matter contained in the above description or shown in the accompanying drawings shall be interpreted as illustrative and not in a limiting sense. It is desired that only such limitations shall be placed upon the invention as are imposed by the prior art or as are specifically set forth in the appended claims.

What is claimed is:

1. In a device for forming and ejecting an ice cube, a container pivotally secured to a portion of a freezing compartment, and an ejector arm having a first leg pivotally secured to said portion and a second leg disposed adjacent a wall of said container, said second leg moving away from said wall as the container and ejector arm are rotated simultaneously so that an ice cube will be ejected from the container.

2. In a device for forming and ejecting an ice cube, a container adapted to be filled with a liquid to be frozen, said container pivotally secured to a first pivot rod, and an ejector arm pivotally secured to a second pivot rod spaced from said first pivot rod, said ejector arm having a leg disposed adjacent the bottom of said container which moves away from said bottom as the container and ejector arm are rotated simultaneously, said leg carrying an ice cube with it and ejecting it from the container.

3. In a device for forming and ejecting an ice cube, a container positioned in a freezing compartment, said container provided with a bottom wall, inclined front and side walls and a back wall, and an ejector arm having a first leg adjacent said back wall and a second leg adjacent said bottom wall, said back wall pivotally secured to a first pivot rod, said first leg pivotally secured to a second pivot rod so that as said container and ejector arm are rotated simultaneously said first leg moves relative to said back wall and said second leg moves away from said bottom wall which ejects an ice cube from the container.

4. In a device for forming and ejecting an ice cube, a container positioned in a freezing compartment, said container having a bottom wall, inclined front and side walls and a back wall which extends above said other walls, a first pivot rod secured to a portion of said freezing compartment, a second pivot rod spaced below said first pivot rod and secured to said portion, said back wall having a socket which fits over said first pivot rod and a semi-circular slot spaced from said socket through which said second pivot rod extends, and an ejector arm having a first leg which is disposed adjacent to said back wall and secured to said second pivot rod and a second leg disposed adjacent said bottom wall, said container and ejector arm adapted to be rotated simultaneously so that said first leg moves relative to said back wall and said second leg moves away from said bottom wall which breaks the bond between the ice cube and the container.

5. In a refrigerator, a door for closing a freezer compartment, an ice forming container pivotally secured to said door, and an ejector arm having a first leg pivotally secured to said door and a second leg disposed adjacent the bottom of said container, said second leg moving away from said bottom as the container and

ejector arm are rotated simultaneously which ejects an ice cube from the container.

6. In a refrigerator, a door for closing a freezer compartment, a first pivot rod secured to said door to which an ice forming container is pivotally secured, an ejector arm pivotally secured to a second pivot rod which is secured to said door in spaced relation to said first pivot rod, said ejector arm having a portion adjacent the bottom of said container which moves away from said bottom as the container is rotated and ejects the ice from the container.

7. In a refrigerator, a door for closing a freezer compartment, a first pivot rod secured to said door to which a plurality of ice forming containers are pivotally secured, a second pivot rod secured to said door in spaced relation to said first pivot rod, a plurality of ejector arms pivotally secured to said second pivot rod, an ejector arm provided for each container, each ejector arm having a first leg pivotally secured to said second pivot rod and a second leg disposed adjacent the bottom of a container, said second leg and said bottom moving apart as the container is rotated so that the ice is ejected from said container.

8. In a refrigerator, a door for closing a freezer compartment, a first pivot rod secured to said door to which an ice forming container is pivotally secured, a second pivot rod spaced from said first pivot rod and secured to said door, said container having a circular slot through which said second pivot rod extends, and an ejector arm pivotally secured to said second pivot rod with a leg adjacent the bottom of said container, said leg moving away from said bottom as the container is rotated which ejects an ice cube from the container.

9. In a device for forming and ejecting an ice cube, a container pivotally secured to a wall of a freezing compartment, and an ejector extending into said container adjacent a wall thereof, said ejector being pivotally secured to said compartment wall so that the ejector will move relative to said container wall when said container and ejector are rotated simultaneously whereby said ice cube is broken free from said container.

10. In a device for forming and ejecting an

ice cube, a container positioned in a freezing compartment, and an ejector extending into said container adjacent a wall thereof, said container and said ejector being pivotally secured to a wall of said compartment at spaced apart locations, said container and ejector being adapted to be rotated simultaneously so that said ejector moves relative to said container wall and breaks the bond between said ice cube and said container.

11. In a device for forming and ejecting an ice cube, a container adapted to be filled with a liquid to be frozen, said container pivotally secured to a first rod which is fastened to the wall of a freezing compartment, and an ejector pivotally secured to a second rod which is fastened to said wall in spaced relation to said first rod, said ejector having a projection disposed adjacent the bottom of said container which moves away from said bottom as the container and ejector are rotated simultaneously, said projection carrying an ice cube with it and ejecting it from the container.

12. In a refrigerator, a door for closing a freezer compartment, a first rod secured to said door to which a plurality of ice forming containers are pivotally secured, a second rod secured to said door in spaced relation to said first rod, a plurality of ejectors pivotally secured to said second rod, each ejector extending into a separate container adjacent a wall thereof, each container adapted to be rotated individually whereby the ejector therein moves relative to the wall of the container and breaks the bond between said ice and said container.
